UNITED STATES PATENT OFFICE.

KARL STEINBECKER, OF CHARLOTTENBURG, GERMANY, ASSIGNOR TO GENERAL ELECTRIC COMPANY, A CORPORATION OF NEW YORK.

CROSS-HEAD.

1,158,328.

Specification of Letters Patent.

Patented Oct. 26, 1915.

Application filed August 7, 1912. Serial No. 713,747.

To all whom it may concern:

Be it known that I, KARL STEINBECKER, a subject of the King of Prussia, residing at Charlottenburg, Germany, have invented 5 certain new and useful Improvements in Cross-Heads, of which the following is a specification.

This invention relates to internal combustion engines, and its object is to provide an 10 improved cross-head for such engines, whereby a saving in material and weight can be effected and also a greater rigidity secured.

The invention is illustrated in the accompanying drawing, which shows in longitudinal section an engine in which two oppositely moving pistons are arranged in the same cylinder, the upper piston being equipped with my improved cross-head.

20 In the cylinder 1 are two pistons 2, 3 which move in opposite directions and control respectively the inlet ports 4 and the outlet ports 5. The lower piston 2 is connected by a pitman 6 with its crank 7 on the common shaft 8. The upper piston 3 is connected with its cranks 9 by the long connecting rods 10, whose upper ends are pivotally attached to the ends of a cross-head fastened to said upper piston.

30 In the drawing this upper piston is shown in section, and is of the trunk type, having a strong head 11 and relatively thin side walls 12 which carry the packing rings 13. The cross-head 14 has a foot 15 which is secured to the head of the piston 3 by bolts 16. From the foot rises a rigid structure, preferably composed of diverging arms 17 cast integral with the foot 15 and united by a bridge 18 at their upper ends. At the 40 ends of this bridge and adjacent to the up-

per ends of said arms are the bearings 19 which slide in the guide slots 20 formed on the upper end of the cylinder 1. Projecting beyond these bearings are the trunnions 21 on which the connecting rods 10 are pivoted. 45

By this construction of the cross-head, the thrust of the piston is transmitted from its axis to the ends of the cross-head near the bearings, thereby giving the structure greater rigidity and shortening the effective 50 length of the two arms of the cross-head. In consequence of the more favorable distribution of the forces, the cross-head may be more lightly constructed, thereby effecting a saving in material and reducing the 55 masses to be accelerated.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means. 65

What I claim as new and desire to secure by Letters Patent of the United States, is:—

A cross-head for a piston comprising a foot secured to the head of the piston, diverging arms extending therefrom, a bridge 70 piece connecting them, bearings formed on said bridge piece adjacent said arms, and trunnions projecting beyond the bearings.

In witness whereof, I have hereunto set my hand this eighteenth day of July, 1912. 75

KARL STEINBECKER.
